200,825

AIRCRAFT

John J. Grebe, 1505 W. St. Andrews Drive,
Midland, Mich.

Filed May 9, 1963, Ser. No. 74,829

Term of patent 14 years

(Cl. D71—1)

Fig. 1

Fig. 3

Fig. 2

FIGURE 1 is a side elevational view of an aircraft with the flaps in closed position showing my new design;

FIGURE 2 is a front elevational view thereof with the flaps in extended position; and

FIGURE 3 is a top plan view thereof with the rudder and flaps in extended position.

The dominant features of this design reside in the configurations shown in full lines on the drawings.

I claim:

The ornamental design for an aircraft, as shown and described.
